[57] **CLAIM**

The ornamental design for the dry wall cutter, as shown and described.

DESCRIPTION

FIG. 1 is a reduced rear, top right side perspective view of a dry wall cutter showing my new design;
FIG. 2 is an enlarged front, top left side view thereof;
FIG. 3 is a front elevational view thereof;
FIG. 4 is a right side elevational view of FIG. 3;
FIG. 5 is a left side elevational view of FIG. 3;
FIG. 6 is a rear elevational view thereof;
FIG. 7 is a top plan view thereof; and
FIG. 8 is a bottom plan view thereof.
The broken lines shown in the drawing are for illustrative purposes only.
